Atty.

UNITED STATES PATENT OFFICE.

CHARLES A. DARR, OF LEAVENWORTH, KANSAS.

ADDING-MACHINE.

957,753.

Specification of Letters Patent. Patented May 10, 1910.

Application filed November 5, 1909. Serial No. 526,412.

To all whom it may concern:

Be it known that I, CHARLES A. DARR, a citizen of the United States, residing at Leavenworth, in the county of Leavenworth 5 and State of Kansas, have invented certain new and useful Improvements in Adding-Machines, of which the following is a specification.

My invention relates to improvements in 10 adding machines, and my object is to provide a simple, inexpensive device of compact form for the convenience of book-keepers, accountants, and the like, in adding columns of figures.

In the accompanying drawing, which 15 illustrates the invention, Figure 1 represents a plan view of the machine. Fig. 2 is a longitudinal section thereof on line II—II of Fig. 3. Fig. 3 is a vertical cross 20 section on line III—III of Fig. 2, and Fig. 4 shows a tool for turning the adding-wheels.

In carrying out the invention, I employ a case 1, having a beveled front side 2, so 25 that it may be employed as a ruler, said beveled side having a scale 3 whereby measurements may be taken.

4, 5 and 6 designate, respectively, units, 30 tens and hundreds adding-wheels. Each adding-wheel is carried by a shaft 7 mounted in the top and bottom of the case, and containing a washer 8 whereby the adding-wheel is supported above the bottom of case 1, as shown in Fig. 3. Each adding-wheel 35 has a circular row of numerals 9, consisting of "0" to "9", inclusive, a circular row of holes 10, and peripheral ratchet-teeth 11, the numerals 9, holes 10, and the abrupt portions of the ratchet-teeth being preferably 40 arranged in radial alinement as shown in Fig. 2.

Adding-wheels 4 and 5 have lugs 12 and 45 13, respectively, each lug being adjacent the numeral "9" on its respective wheel. Lugs 12 and 13 depend in the path of lugs 14 and 15, extending laterally from the rear terminals of a pair of propelling arms 16 and 17, respectively, slidably-mounted upon the bottom portion of the case, and retained 50 in position thereon by screws 18 and staples 19. Each screw 18 extends through a longitudinal slot 20 in a flange 21 on each arm while staples 19 extend through longitudinal slots 22 in the forward portions of 55 the arms. The forward ends of the propelling-arms 16 and 17 are held adjacent

the ratchet-teeth of the adding-wheels 5 and 6 by springs 23 and 24, respectively, bearing at their free ends against said arms, and secured at their opposite ends to screws 25. 60

26 and 27 designate levers engaging the propelling-arms 16 and 17, respectively, and pivotally-mounted upon pins 28 and 29 projecting upwardly from the bottom of the case. 65

30, 31, and 32 designate resilient arms normally engaging at their free ends to the rear side of case 1, as shown in Fig. 2.

33 designates a push-bar slidably-mounted in the rear side of the case and a guide 70 34, which latter is adjacent the units wheel 4. Push-bar 33 is provided at its outer end with a knob 35, and at its inner end with a pin 36, which latter is normally held in engagement with guide 34 by a retractile 75 spring 37 secured at its ends to the back of the case and the push-bar. Push-bar 33 is provided with a pivotally-mounted pawl 38 which is held in engagement with the ratchet-teeth of the units wheel 4, by a 80 spring 39. The upper part of case 1 is provided with segmental slots 40 to expose openings 10 in the adding-wheels, so that a pencil, or a tool 41 may be inserted into any of said openings for the purpose of 85 turning said wheels. Tool 41 is provided with a pin 42 for entering any of the openings 10, the entrance of the pin being limited by a shoulder 43, which slides around upon the upper surface of the case. 90

44 designates circular rows of numerals "0" to "9" inclusive, arranged adjacent slots 40, the rear ends 45 of which latter act as stops for the tool 41. The numerals "0" of the rows 44 are arranged diametrically 95 opposite the numerals "0" on the adding-wheels when the same are arranged at zero or the starting point, which may be determined by bringing the "0's" on the adding-wheels in coincidence with a plurality of 100 sight-openings 46 in the top of the case.

In operation the adding-wheels, commencing with the units wheel, at the right-hand end of the machine, are rotated until the "0" of each is disclosed through its respective sight-opening 46. This is accomplished by turning each wheel with the tool 41 in the direction of arrow *a*. Assuming that the first figure of a column to be added is "9", the point of the tool is inserted in the opening of the units wheel opposite "9" of the row 44, and the units wheel is turned 110

until pin 42 contacts with the rear terminal 45 of slot 40. This will bring the numeral "9" of the units wheel into coincidence with its respective sight-opening 46. If the next figure to be added is 7, the point of the tool is inserted in the opening of the units wheel opposite "7" of row 44, and the units wheel is turned until pin 42 contacts with the terminal 45 of slot 40. This operation will bring the numeral "6" on the units wheel into coincidence with the sight-opening 46. As the units wheel is turned its depending lug 12 engages the lug 14 of the propelling-arm 16 and pushes the same forward to the dotted position shown in Fig. 2, causing it to turn the tens wheel until its numeral "1" is brought into coincidence with its respective sight-opening 46. The two numerals thus disclosed equal the amount of the added numbers, which is 16. As the propelling-arm 16 moves forward, it actuates lever 26, and throws the free terminal of the same into the path of lug 13, so that when the units wheel is turned to add the numeral "7" said lug will engage the lever and restore it to normal position. As the lever moves back to normal position, it carries the propelling-arm 16 therewith. While the wheels are free to rotate in the direction of arrow *a*, they are held from backward rotation by the resilient arms 30, 31, and 32. At times it is inconvenient to actuate the adding-wheels with the tool 41, in which case the tool may be dispensed with and the operation of turning the adding-wheels be accomplished through the intermediary of push-bar 33 and its pawl 38.

Having thus described my invention, what I claim is:

- 40 1. An adding machine consisting of a case having slots in its top and sight-openings adjacent said slots, numerals arranged around said slots, a series of adding-wheels beneath the slots of increasing denominations from right to left and provided with rows of numerals corresponding to the numerals arranged around the slots, said adding-wheels being provided with peripheral ratchet-teeth, lugs on all the adding-wheels but the one of highest denomination, propelling-arms slidingly-mounted in the case to transmit motion from a wheel of lower denomination to one of higher denomination, each arm being arranged in the path of a lug on one wheel and adjacent a ratchet-tooth of the following wheel, and levers engaging said arms to restore the same to normal, said levers being actuated by the lugs which actuate the propelling-arms.
- 50 2. An adding machine consisting of a case having slots in its top and sight-openings adjacent said slots, numerals arranged around said slots, a series of adding-wheels beneath the slots of increasing denominations from right to left and provided with

rows of numerals corresponding to the numerals arranged around the slots, said adding-wheels being provided with peripheral ratchet-teeth, lugs on all the adding-wheels but the one of highest denomination, 70 propelling-arms slidingly-mounted in the case to transmit motion from a wheel of lower denomination to one of higher denomination, each arm being arranged in the path of a lug on one wheel and adjacent a ratchet-tooth of the following wheel, levers engaging said arms to restore the same to normal, 75 said levers being actuated by the lugs which actuate the propelling-arms, and means engaging the ratchet-teeth to prevent backward rotation of the wheels.

3. An adding machine consisting of a case having slots in its top and sight-openings adjacent said slots, numerals arranged around said slots, a series of adding-wheels 85 beneath the slots of increasing denominations from right to left and provided with rows of numerals corresponding to the numerals arranged around the slots, said adding-wheels being provided with peripheral ratchet-teeth, lugs on all the adding-wheels but the one of highest denomination, 90 propelling-arms slidingly-mounted in the case to transmit motion from a wheel of lower denomination to one of higher denomination, each arm being arranged in the path of a lug on one wheel and adjacent a ratchet-tooth of the following wheel, levers engaging said arms to restore the same to normal, said levers being actuated by the lugs which actuate the propelling-arms, and 95 resilient arms engaging the ratchet-teeth to prevent backward rotation of the wheels.

4. An adding machine consisting of a case having segmental slots in its top and sight-openings adjacent said slots, numerals arranged around said slots, a series of adding-wheels beneath the slots of increasing denominations from right to left and provided with rows of numerals corresponding to the numerals arranged around the slots, said adding-wheels being provided with ratchet-teeth and circular rows of openings, lugs on all the adding-wheels but the one of highest denomination, propelling-arms slidingly-mounted in the case to transmit motion from a wheel of lower denomination to one of higher denomination, each arm being arranged in the path of a lug on one wheel and adjacent a ratchet-tooth of the following wheel, and levers engaging said arms to restore the same to normal, said levers being actuated by the lugs which actuate the propelling-arms; in combination with a tool 110 having a reduced end adapted to extend through any of the segmental slots and any of the openings in the adding-wheels, said tool having a shoulder to slidingly-engage 115 the upper surface of the case.

5. An adding machine consisting of a case 120

having slots in its top and sight-openings adjacent said slots, numerals arranged around said slots, a series of adding-wheels beneath the slots of increasing denominations from right to left and provided with rows of numerals corresponding to the numerals arranged around the slots, said adding-wheels being provided with peripheral ratchet-teeth, lugs on all the adding-wheels but the one of highest denomination, propelling-arms slidably-mounted in the case to transmit motion from a wheel of lower denomination to one of higher denomination, each arm being arranged in the path of a lug on one wheel and adjacent a

ratchet-tooth of the following wheel, levers engaging said arms to restore the same to normal, said levers being actuated by the lugs which actuate the propelling-arms, a push-bar slidably-mounted in the case adjacent the adding-wheel of lowest denomination, and a pawl carried by said push-bar and adapted to engage the teeth of the last-mentioned adding-wheel.

In testimony whereof I affix my signature, 25
in the presence of two witnesses.

CHARLES A. DARR.
